[57] CLAIM

The ornamental design for a shield against electromagnetic waves for use on portable phone, as shown and described.

DESCRIPTION

FIG. 1 is a top view of the shield against electromagnetic waves for use on a portable phone, the bottom view being a mirror thereof showing my new design;

FIG. 2 is a right side view thereof, the left side view being a mirror image thereof;

FIG. 3 is a front view thereof, the rear view being a mirror image thereof; and,

FIG. 4 is a perspective view showing the shield against electromagnetic waves as mounted over a speaker on a portable phone, shown in phantom.

The broken line showings of FIG. 4 are for illustrative purposes only and forms no part of the claimed design.
